UNITED STATES PATENT OFFICE

NESTOR F. SMITH, OF ITHACA, NEW YORK, ASSIGNOR TO ITHACA GUN COMPANY, OF
ITHACA, NEW YORK

RECOIL PAD FOR GUNS

Application filed January 19, 1932. Serial No. 587,577.

This invention relates to certain new and useful improvements in recoil pads for guns.

The primary object of the invention is to provide a recoil pad for guns embodying a soft rubber block constituting the shoulder engaging portion of the pad and a semi-hard base carried by the soft rubber block to be engaged with the butt end of a gun stock to facilitate the attachment of the recoil pad to the gun stock with a relatively large depression in the outer face of the semi-hard base possessing the characteristics of a vacuum cup or suction device and assuring snug and intimate contact between the recoil pad and gun stock.

It is a further important object of the invention to provide transversely extending openings in the shoulder engaging soft rubber block in fanlike series radiating from the base portion of the soft rubber block and of gradually increasing length and angles relative to the transverse median line of the pad to insure an even distribution of pressure on the recoil pad during recoil of the gun and to cause the recoil pad to shape itself to the shoulder of the user with pressure evenly distributed thereover for the lessening of recoil shock at any particular point.

With the above and other objects in view that will become apparent as the nature of the invention is better understood, the same consists in the novel form, combination and arrangement of parts hereinafter more fully described, shown in the accompanying drawing and claimed.

In the drawing:

Figure 1 is an outer end elevational view of the recoil pad for guns constructed in accordance with the present invention;

Figure 2 is a side elevational view of the recoil pad with a part of the gun stock fragmentarily illustrated and showing the fan-like series of openings extending transversely through the soft rubber block of the recoil pad;

Figure 3 is a bottom plan view of the recoil pad showing the depression in the semi-hard base thereof that faces the butt end of the gun stock;

Figure 4 is a cross-sectional view taken on line 4—4 of Figure 2 with the gun stock removed showing transverse openings in the soft rubber block and the depression in the semi-hard base of the recoil pad; and

Figure 5 is a cross-sectional view taken on line 5—5 of Figure 2, showing the opening through the pad for the passage of the pad attaching means to the gun stock.

The recoil pad comprises a soft rubber block 10 that is vulcanized or otherwise secured to a semi-hard base 11, the recoil pad being secured to the butt end of a gun stock 12 by fastening devices, such as screws extending through registering openings 13 provided in the soft rubber block and semi-hard base.

The semi-hard base 11 at the side thereof facing the butt end of the gun stock 12 is provided with a depression 14 of a configuration following the outline of the gun pad and functions as a vacuum or suction cup when engaged with the butt end of the gun stock to insure a snug and intimate contact between the recoil pad and the gun stock.

The soft rubber block 10 of the recoil pad has its end face 15 of the usual design or curvature common to pads of this character and said soft rubber block is provided with a series of transversely extending non-communicating openings formed and related in a manner to effect even distribution of pressure on the soft rubber block during recoil for the elimination of the centering of shock at any particular point. As shown more clearly in Figure 2, an opening 16 of segment form is arranged intermediate the ends of the soft rubber block 10 with the chordal line thereof in proximity of the semi-hard base 11 and a series of transverse openings 17 in the soft rubber block are of fan-like formation, gradually increasing in length from a central point outwardly with the longitudinal axis of each opening 17 of increasing angles outwardly relative to the transverse diameter of the recoil pad. The walls between the transverse openings 16 and 17 also gradually increase in angles from the center line outwardly and with respect to the plane of the semi-hard base with the walls nearer the ends

of the pad approaching the plane of the base. Also, the walls gradually increase in thickness from their inner ends outwardly to provide increased flexibility in the walls and 5 cushioning effect of the pad. By arranging the openings 16 and 17 in a manner as described, increased cushioning effect during recoil of the gun is effected as well as a more even distribution of pressure over the pad so 10 that the user of the gun is not inconvenienced by sudden shocks or jolts incident to recoil and the soft rubber pad shapes itself to the contour of the shoulder of the user.

From the above detailed description of the 15 invention, it is believed that the construction and use of the pad will at once be apparent, and while there is herein shown and described the preferred embodiment of the invention, it is nevertheless to be understood that minor 20 changes may be made therein without departing from the spirit and scope of the invention as claimed.

I claim:—

1. In a recoil pad for guns wherein the pad 25 is formed of flexible material and said pad having a series of transversely extending openings therethrough arranged in fan-like formation radiating from the center of the pad and defining openings and spacing walls 30 of gradually increasing lengths for the even distribution of pressure in the presence of recoil action.

2. In a recoil pad for guns wherein the pad 35 is formed of flexible material and said pad having a series of transversely extending openings therethrough arranged in fan-like formation radiating from the center of the pad for the even distribution of pressure in the presence of recoil action, said openings 40 successively increasing in length from the transverse median line of the pad towards the outer ends and the walls separating the openings adjacent the ends gradually increasing in thickness from the inner to the outer 45 side of the pad.

3. In a recoil pad for guns wherein the pad 50 is formed of flexible material and said pad having a series of transversely extending openings therethrough arranged in fan-like formation radiating from the center of the pad for the even distribution of pressure in the presence of recoil action, the longitudinal axes of the openings successively increasing in angles relative to the transverse axis of 55 the pad in directions towards each end of the pad.

4. In a recoil pad for guns wherein the pad 60 is formed of flexible material and said pad having a series of transversely extending openings therethrough arranged in fan-like formation radiating from the center of the pad for the even distribution of pressure in the presence of recoil action, said openings 65 successively increasing in length from the transverse median line of the pad towards the

outer ends, the longitudinal axes of the openings successively increasing in angles relative to the transverse axis of the pad in directions towards each end of the pad.

5. In a recoil pad for guns, a pad having 70 a semi-hard base for attachment to a gun stock and a soft rubber block secured to the semi-hard base with transverse openings therein arranged in fan-like formation radiating from the transverse median line of the pad and a segment-shaped opening midway the ends of the pad with its chordal line adjacent and parallel with the semi-hard base and inwardly of adjacent openings. 75

6. In a recoil pad for guns wherein the pad 80 is formed of flexible material with a semi-hard base, said pad having a series of transversely extending openings therethrough arranged in fan-like formation radiating from the center of the pad, walls spacing the openings with the longitudinal axes of the walls 85 successively decreasing in angularity relative to the base from the center outwardly.

In testimony whereof I affix my signature.
